DESIGN FOR A PAIR OF SHEARS

Herbert Wester, Millburn, N. J., assignor to the firm Wester Bros., New York, N. Y.

Application April 28, 1939, Serial No. 84,644

Term of patent 14 years

To all whom it may concern:

Be it known that I, Herbert Wester, a citizen of the United States and a resident of Millburn, county of Essex, and State of New Jersey, have invented a new, original, and ornamental Design for a Pair of Shears, of which the following is a specification, reference being had to the accompanying drawing, forming part thereof, in which—

I claim:

The ornamental design for a pair of shears, substantially as shown.

HERBERT WESTER.
